UNITED STATES PATENT OFFICE.

OSCAR C. ARLITZ, OF NEW YORK, N. Y., ASSIGNOR TO LOVELL-McCONNELL MANUFACTURING COMPANY, A CORPORATION OF DELAWARE.

MECHANICAL HORN.

1,110,032.

Specification of Letters Patent.

Patented Sept. 8, 1914.

Application filed March 3, 1911. Serial No. 611,961.

To all whom it may concern:

Be it known that I, OSCAR C. ARLITZ, a citizen of the United States, residing at the borough of Manhattan, in the city, county, and State of New York, have invented certain new and useful Improvements in Mechanical Horns, of which the following is a specification, reference being had therein to the accompanying drawings, which form 10 a part thereof.

My invention relates to mechanical horns and more particularly to a type thereof employing a mechanically flexed diaphragm.

The main object of the invention is to 15 provide a horn of this character wherein the diaphragm will be flexed by an impact member adapted to recede with the diaphragm upon the reflex action thereof beyond its normal plane, said impact member 20 being adapted to, and capable of receiving movement in one direction by intermittent pulsations applied in a manner not to interfere with the movement of said impact member with, and under the control of, the diaphragm upon the reflex action thereof.

A further object is to provide a horn of 30 this character wherein the diaphragm will be flexed to the maximum desirable degree with a minimum expenditure of energy, thus lending economy to the actuation of the horn and at the same time reducing the cost of production as to the actuating mechanism itself.

A still further object is to provide a horn 35 of this character wherein the flexure of the diaphragm will be accomplished through an elastic impact member interposed between the rotary striking member and said diaphragm, thus relieving the diaphragm 40 itself from that wiping action incidental to the direct contact of the striking member with the diaphragm and eliminating any possibility of injury resulting to the diaphragm impact member, or of the diaphragm adjacent thereto, from sharp impacts between said diaphragm impact member and the co-operating diaphragm flexing member. And a still further object is to 45 provide a horn of this character wherein the striking member will impart substantially the maximum flexure to the diaphragm irrespective of the position of the diaphragm 50 upon the reflex action thereof when the

striking member is operative relative to the diaphragm.

The invention consists primarily in a mechanical horn embodying therein such other novel features of construction and combination of parts as are hereinafter set forth and described, and more particularly pointed out 55 in the claims hereto appended.

Referring to the drawings:—Figure 1 is a longitudinal section through a horn embodying my invention; Fig. 2 is a vertical lateral section thereof; and Fig. 3 is a horizontal view illustrating the mode of operation of the horn.

Like letters refer to like parts throughout the several views.

In the embodiment of my invention shown 70 in the accompanying drawings, *a* indicates a horn casing toward the forward end of which is mounted in any desired manner a flexible metallic diaphragm *b* provided centrally thereof with a single impact stud or 75 reinforcement *c*. The casing, forwardly of the diaphragm *b* is provided with a sound outlet opening at *d*, projecting from which is an ordinary horn or amplifier *e*.

This general construction and arrangement is old and well known in this art, and no claim of invention is made thereto broadly. It has been found in practice, however, that to prolong the life or preserve the elasticity of the diaphragm, it is essential 85 to provide a clear field of vibration therefor upon both sides of the normal plane of the diaphragm, any limitation placed upon the reflex action thereof tending toward crystallization resulting in a 90 permanent displacement of the effective flexing area of the diaphragm about the stud *c*, and in a loss of efficiency in the horn.

The main actuating mechanism, I have shown as consisting of a motor *f*, upon the 95 shaft of which is mounted a striking member *g* comprising a disk having a sequence of rises *h* on the face thereof, said rises being arranged in a circle and being equi-distant. While this construction is desirable, 100 as permitting a compact structure, any other desired appropriate type of striking mechanism may be substituted therefor without departing from my invention in its broader aspects.

Mounted so as to have a fixed position

relative to the striking member *g* and the normal plane of the diaphragm *b*, as upon the fixed support *i* carried by the casing *a*, or the motor casing, is a vibratory member *j* which projects upon a plane parallel to the plane of the diaphragm, the free end of said vibratory impact member carrying a stud or reinforcement *k* adapted to engage the stud or reinforcement *c* upon the diaphragm. 5 This vibratory member is preferably made of spring metal, the elasticity of which is slightly greater than that of the diaphragm, which elasticity will vary with any variance in that of the diaphragm employed. Upon 10 the side of the member *j* away from the diaphragm and toward the striking member *g* is a wear stud or impact member *l* adapted to be engaged by the said striking member, the vibratory member *j* thus being interposed between the striking member and the diaphragm. 15

To insure the maximum flexure of the diaphragm with the minimum effective displacement of the interposed member *j*, by 20 the striking member *g*, I arrange the stud *l* adjacent to the point of support of the member *j*.

The operation of the herein described horn is substantially as follows: When it is 25 desired to sound a signal, the circuit to the motor *f* is closed, or any other desired means for actuating the striking member *g* made operative, to rotate the member *g* at high speed. As the member *g* is rotated, it will 30 impart to the impact member *l* upon the vibratory member *j* a series of sharp impulses forcing said vibratory member, and with it the diaphragm, forwardly in a manner to flex or displace said diaphragm from normal. The lower elasticity of the member *g* 35 and the high frequency of the impulses from the striking member *g* will quickly set the diaphragm *b* in motion with a resultant development of sound waves projected through the sound opening *d* and amplifier *e*. While 40 the stud *c* and wear member *k* upon the member *j* are preferably used to protect the diaphragm, the reciprocatory movement of the said member *j* will reduce the wear upon 45 the diaphragm to a minimum so that such studs are not absolutely essential. They do, however, permit the member *j* to be spaced away from the diaphragm so that said member is without the greatest plane of displacement 50 of the diaphragm upon the reflex action thereof. After the pressure by the member *j* upon the diaphragm has flexed it to the greatest extent under a rise *h* upon the striking member *g*, a reflex action of 55 said diaphragm occurs which carries the member *j* not only to the normal plane of the diaphragm, but beyond said plane, the moving inertia of these parts causing the member *j* to flex at the point of contact with 60 the striking member *g* and to move in syn-

chronism with the diaphragm upon any reflex movement thereof beyond its normal plane. Should there be a loss of synchronism in the flexing of the diaphragm and the impulses from the striking member *g*, the 65 same condition as to the flexure of the member *j* will exist as upon the full reflex action of the diaphragm. This construction and arrangement permits the application of the full force of each impulse or impact by the 70 striking member *g* to the interposed member without subjecting the diaphragm to a dead impact, thus minimizing the tendency of a crystallization of the diaphragm and prolonging the life and efficiency thereof. By 75 causing the striking member to engage the interposed member adjacent to one end thereof, I secure a sufficient leverage in the application of the impulses to the diaphragm to permit a small displacement of 80 the interposed member at the point of contact with the striking member, as compared to the effective displacement of the diaphragm under said interposed member. This, together with the reduction of friction 85 between the striking member and the interposed member, reduces the power required to operate the horn, thus securing economy of operation and cheapness in production owing to the lower cost of low 90 power motors.

It is not my intention to limit the invention to the precise details of construction shown in the accompanying drawings, such being largely matters of design and capable of 95 variation without departing from the spirit or scope of the invention.

Having described my invention, what I claim as new and desire to have protected by Letters Patent, is:—

1. In a mechanical horn, a flexible diaphragm, a flexible vibratory impact member, one end of which is normally spaced away from and adapted to engage and flex said diaphragm, a support for the other end 100 of said vibratory member independent of the vibratory portion of the diaphragm, a striking member adapted to engage said vibratory member intermediate its ends and force it into engagement with said diaphragm whereby the flexibility of said impact member will permit it to have return movement with the diaphragm independently of said striking member, and means actuating said striking member.

2. In a mechanical horn, a flexible diaphragm, a flexible vibratory impact member, one end of which is normally spaced away from and adapted to engage and flex said diaphragm, a support for the other end of 115 said vibratory member independent of the vibratory portion of the diaphragm, a striking member having a succession or series of rises thereon adapted to engage said vibratory member intermediate its ends and

force it into engagement with said diaphragm whereby the flexibility of said member will permit it to have return movement with the diaphragm independently of said striking member, and means actuating said striking member.

3. In a mechanical horn, a flexible diaphragm, a flexible vibratory impact member normally spaced away from and one end 10 of which is adapted to engage and flex said diaphragm, a support for the other end of said vibratory member independent of the vibratory portion of the diaphragm, a striking member having a succession or series of 15 rises thereon adapted to engage said vibratory member intermediate its ends, whereby said vibratory member is adapted to automatically return to its normal position within the operative plane of said striking member 20 and the end of said impact member engaging and flexing the diaphragm, is adapted to pass said normal position under the control of said diaphragm irrespective of the position of said striking member, and 25 means actuating said striking member.

4. In a mechanical horn, a flexible diaphragm having a central wear stud thereon, a vibratory impact member spaced away from said diaphragm, one end of which member 30 carries a stud adapted to engage the stud upon said diaphragm, a support for the other end of said member independent of the vibratory portion of the diaphragm, a striking member adapted to engage said 35 vibratory member intermediate its ends and force it into engagement with said diaphragm, and means actuating said striking member.

5. In a mechanical horn, a flexible diaphragm, a vibratory impact member, one end of which is adapted to engage and flex said diaphragm, a fixed support for the other end of said vibratory member independent 40 of the vibratory portion of the diaphragm, a striking member adapted to engage said vibratory member adjacent to its support and force it into engagement with said diaphragm whereby small displacement of said vibratory member at the point of engagement with said striking member secures a 45 large displacement thereof at the point of engagement with the diaphragm, and means actuating said striking member.

6. In a mechanical horn, a flexible diaphragm, a flexible vibratory impact member having less elasticity than said diaphragm, one end of which member is adapted to engage and flex said diaphragm, a support for the other end of said vibratory member independent of the vibratory portion of the diaphragm, a striking member 55 adapted to engage said vibratory member intermediate its ends, and means actuating said striking member.

7. In a mechanical horn, a flexible diaphragm, a flexible vibratory impact member extending parallel to the normal plane of said diaphragm, one end of which impact member is adapted to engage and flex said diaphragm, a support for the other end 60 of said vibratory member independent of the vibratory portion of the diaphragm, and means adapted to engage said vibratory impact member intermediate its ends and force it into engagement with said diaphragm 65 with a series of impulses whereby said impact member is automatically restored to its normal plane and is permitted at its point of engagement with the diaphragm 70 to have movement upon said plane irrespective of the position of said means.

8. In a mechanical horn, a flexible diaphragm, a flexible vibratory impact member parallel to the normal plane of said diaphragm and normally disengaged therefrom, one end of which impact member is adapted to be forced into engagement with, and to flex, said diaphragm, a support for the other end of said vibratory member independent of the vibratory portion of the 85 diaphragm, a striking member adapted to engage said vibratory member intermediate its ends whereby said member is permitted to flex with, and upon the reflex action of, said diaphragm, and means actuating said 90 striking member.

In witness whereof, I have hereunto affixed my signature, in the presence of two subscribing witnesses, this 25th day of February, 1911.

OSCAR C. ARLITZ.
